UNITED STATES PATENT OFFICE.

LEONIDAS D. WEST, OF DENVER, COLORADO.

AIR-HEATER FOR STOVES AND FURNACES.

1,390,947.

Specification of Letters Patent. Patented Sept. 13, 1921.

Application filed January 7, 1920. Serial No. 350,054.

To all whom it may concern:

Be it known that I, LEONIDAS D. WEST, a citizen of the United States, residing at Denver, in the county of Denver and State 5 of Colorado, have invented certain new and useful Improvements in Air-Heaters for Stoves and Furnaces; and I do declare the following to be a full, clear, and exact description of the invention, such as will enable others skilled in the art to which it 10 appertains to make and use the same.

My invention relates to improvements in stove and furnace attachments, and more particularly to those designed for feeding 15 a quantity of highly heated and expanded air to the fire-box or other appropriate internal chamber, for the purpose of increasing combustion, saving fuel, and consuming the greater part of the smoke which ordinarily escapes, carrying with it valuable 20 heat units.

One object of the invention is to provide an extremely simple and inexpensive device for the above named purpose, which may be 25 manufactured and marketed to advantage, and applied to numerous forms of stoves and furnaces without the necessity of making any alterations therein.

Another object is to provide an attachment 30 of the class set forth which may be used to great advantage with a supplemental air-heating casing, to receive pre-heated air from the latter, superheating and highly expanding such air, and discharge it 35 in jets into the fire-box or the like.

With the foregoing and minor objects in view, the invention resides in the novel construction and arrangement of parts herein-after described and claimed, the descriptive 40 matter being supplemented by the accompanying drawings.

Figure 1 is a plan view of one of the improved air heaters used in connection with a supplemental air-heater mounted on a furnace door.

Fig. 2 is an inner side elevation of the parts shown in Fig. 1.

Fig. 3 is an edge view.

Fig. 4 is a vertical section on the plane 50 indicated by line 4—4 of Fig. 2.

Fig. 5 is a perspective view of the ribbed plate forming a part of the air-heater.

Fig. 6 is a perspective view of the cover plate for the ribbed plate shown in Fig. 5.

Fig. 7 is a perspective view showing one 55 of the air heaters attached to a stove lid.

Fig. 8 is a sectional view on the plane indicated by the line 8—8 of Fig. 7.

Fig. 9 is a bottom plan view of the ribbed plate shown in Figs. 7 and 8.

Fig. 10 is a transverse section as indicated by the lines 10—10 of Figs. 8 and 9.

Fig. 11 is an elevation showing air heaters of different shape than those illustrated in the other views.

In carrying out my invention, I employ a casing 1 adapted to be exposed to heat within a stove or furnace, said casing having an air inlet neck 2 whose outer end is adapted to abut and be closed by a stove lid 3 as 70 shown in Figs. 7 to 10, by one wall 4 of an auxiliary air-heating casing 5 as depicted in Figs. 1 to 4, or by any other appropriate stove or furnace part. In all instances, this part will be provided with one or more air 75 inlet perforations 6. A web 7 extends across the inner end of the neck 2 and is provided with restricted openings 8 through which the air must pass from said neck into the casing 1. This perforated web coacts with 80 the neck and the stove or furnace part against which said neck is clamped, to produce an auxiliary air-heating chamber 9 in which preheating and considerable expansion of the air takes place before it enters 85 the casing 1, and since the perforations 8 are rather small the passage of air from the chamber 9 into the casing 1 is retarded to such an extent as to insure heating of the air to a high temperature and high expansion of such air before it enters the casing 1.

Within this casing, due to a novel arrangement of ribs, the air is superheated, and is in a highly heated and expanded state when it is finally discharged into the 95 fire-box or the like.

In the preferred embodiment of my invention, I construct the casing 1 of a ribbed plate 10 and a cover plate 11, both of which are by preference of substantially Y shape, 100 and for future reference, I have designated the shank of the plate 10 by numeral 12, and its diverging arms by the character 13. The edges of all of these parts are provided with a continuous lateral flange 14 which may be provided at the ends of the arms 13 with a plurality of small air outlet notches 15 as seen in Figs. 2 and 5, or with wider air inlets 15* as in Figs. 7 and 9. When the latter construction is used air deflecting flanges 110 16 preferably extend outwardly from the flange 14, adjacent the openings 15* as seen

clearly in Figs. 7, 8 and 9. The air enters the casing 1 through the perforations 8 and before reaching the outlets 15 or 15^a is forced to travel along tortuous courses which insure maximum heating thereof.

The air courses above referred to are formed in a simple manner by casting ribs on the plate 10, the arrangements of ribs being illustrated most clearly in Figs. 5 and 10 9. Two longitudinal ribs 17 extend along the shank 12 and arms 13, with their ends in spaced relation with the outer ends of said shank and arms, said ribs being approximately parallel with the adjacent parts 15 of the flange 14. Short transverse ribs 18 join the intermediate portions of the ribs 17 with the portions of the flange 14 at the inner edges of the arms 13, and angular transverse ribs 19 are joined at their outer 20 ends to the parts of the flange 14 at the outer extremities of the arms 13, said ribs 19 extending inwardly between the outer ends 20 of the ribs 17 and the portions of the flange 14 at the inner edges of the aforesaid arms 25 13. The neck 2 may be located to discharge the air in the space partly surrounded by the ribs 17 and 18 as shown in Fig. 9, or may be positioned at the free end of the shank 12 as disclosed in Fig. 5. In either 30 case, the highly heated and expanded air from the perforations 8 must flow through the tortuous channels between the several ribs as indicated by the arrows, and during its travel, the air will be highly heated before it is finally discharged through the outlets 15 or 15^a.

The cover plate 11 is provided, except at the ends and inner edges of its arms, with parallel ribs 21 which straddle the flange 40 14 to properly position the cover plate, and in addition to performing this function, the innermost of said ribs 21, serves to carry heat inwardly into the hot air channels, to produce further efficiency. This last named 45 effect may be increased also by providing the cover plate 11 with one or more additional ribs 22, and I may also equip said plate with small projections 23 to extend into the air outlets, if desired, whereby to 50 split up the discharged air into a plurality of jets.

I preferably use two bolts 24 and 24' for securing the cover plate 11 in place, and the bolt 24' preferably passes longitudinally 55 through the neck 9 to clamp the outer end of said neck against the stove lid 3, the wall 4, or against any other suitable stove or furnace part. When the device is used in connection with a kitchen range or other stove, 60 the neck 2 is clamped directly against one of the lids as seen in Figs. 7, 8 and 10, but when it is employed in connection with a furnace, I prefer that the supplemental heater 5 be used, and this heater may be 65 secured to a furnace door 25 as shown in

Figs. 1 to 4, or to any other suitable part. Such part however, will in all instances have an appropriate air-inlet such as 26, which may well be controlled by a suitable damper 27.

The casing 5 is preferably of the shape shown in the drawing, with one side abutting and closed by the door or the like 25, while its opposite side, here indicated at 70 4, is inclined downwardly and inwardly to 75 similarly position the casing 1.

I attach great importance to the provision of the perforated web 7 which coacts with other parts in forming the air preheating chamber 9, since I have found by actual use 80 that these parts serve to choke down the inrush of air and thus cause more effective heating and expansion thereof. I also consider the simple construction of the entire device as highly important, since it permits 85 easy and inexpensive manufacture and marketing, and well adapts the device to stoves and furnaces of numerous kinds, without the necessity of making any alterations whatever in their construction, only re- 90 quires that one or more holes be drilled. The supplemental air-heater 5 as constructed and associated with the heater 1 is of great importance, since it insures a large reserve supply of warm air, but I 95 make no broad claim to the combination of the supplemental air heater and final air heater, since this is old in the art.

Since excellent results may be obtained from the several details shown and described, they may well be followed, but I 100 wish it understood that within the scope of the invention as claimed, numerous minor changes may well be made.

I claim:

1. A device of the class described comprising a plate having a shank and two arms diverging therefrom in the same plane therewith, the edge of said plate having a continuous flange provided with air outlet 110 openings at the ends of said arms; said shank and the contiguous arm portions having longitudinal ribs terminating short of their outer ends and parallel with the adjacent portions of said flange; transverse 115 ribs joining the intermediate parts of said longitudinal ribs with the portions of said flange at the inner ends of said arms, and angular transverse ribs extending inwardly from the portions of said flange at the outer 120 ends of said arms; said angular ribs extending along said arms between one end of said longitudinal ribs and the parts of said flange at the inner edges of said arms, and terminating in spaced relation with 125 said first named transverse ribs; a cover plate secured against the edges of said flange and ribs, and an air inlet through the aforesaid shank for supplying air to the several channels between the ribs. 130

2. A device of the class described comprising a plate having a shank and two arms diverging therefrom in the same plane therewith, the edge of said plate having a 5 continuous flange provided with air outlet openings at the ends of said arms; said shank and the contiguous arm portions having longitudinal ribs terminating short of their outer ends and parallel with the adjacent portions of said flange; transverse 10 ribs joining the intermediate parts of said longitudinal ribs with the portions of said flange at the inner ends of said arms, and angular transverse ribs extending inwardly 15 from the portions of said flange at the outer ends of said arms; said angular ribs extending along said arms between one end of said longitudinal ribs and the parts of said flange at the inner edges of said arms,
- and terminating in spaced relation with said first named transverse ribs; a cover plate secured against the edges of said flange and ribs, an air inlet neck extending from said shank, means for clamping the outer end of said neck against an apertured stove lid or 20 other furnace of stove part, and a perforated air retarding web across said air inlet neck. 25
3. A structure as specified in claim 1; together with projections on said cover plate extending into said air outlet openings. 30

Signed at Denver, in the county of Denver and State of Colorado, this 31st day of December, 1919.

LEONIDAS D. WEST.
